UNITED STATES PATENT OFFICE.

EDGAR D. MISNER, OF DETROIT, MICHIGAN, ASSIGNOR, BY MESNE ASSIGNMENTS, TO UNIVERSAL APPLIANCES INC., OF DETROIT, MICHIGAN, A CORPORATION OF MICHIGAN.

DRIVE MECHANISM FOR WASHING MACHINES.

Application filed May 15, 1922. Serial No. 560,984.

The invention relates to washing machines and refers particularly to the drive mechanism therefor. The invention has among its objects the provision of a washing machine 5 which is efficient in operation, simple in construction, and can be cheaply manufactured; the provision of a frame for the washing machine which encloses the wiring extending between the electric motor and the connecting 10 trol switch; the provision of a clutch including a driving clutch member and a pair of driven clutch members adapted to be operatively connected thereto independently of each other; the provision of a cam groove 15 in one of the driven clutch members engageable in by the tub actuating lever; the provision of a shaft adapted to be operatively connected to the wringer rolls and to the second driven clutch member, this shaft 20 forming the bearing for the driving clutch member and the first-mentioned driven clutch member; and the provision of a housing for the clutch which constitutes a part of the washing machine frame.

25 With these as well as other objects in view, the invention resides in the novel features of construction and combination and arrangements of parts as more fully herein-after set forth.

30 In the drawings:

Figures 1 and 2 are perspective views of a washing machine embodying my invention;

Figure 3 is a longitudinal cross section 35 through the clutch mechanism;

Figures 4 and 5 are respectively cross sections on the line 4-4 and 5-5 of Figure 3;

Figure 6 is a plan view of the clutch mechanism with the upper part of the housing 40 and the mechanism above the upper driven clutch member removed.

1 is the frame of the washing machine, 2 the rockable tub journaled at its ends upon the frame, and 3 the wringer rotatable 45 through a horizontal path above the tub. 4 is the electric motor mounted upon the frame near one corner thereof and below the tub and adapted to actuate both the tub and wringer through the clutch mechanism 50 within the housing 5.

This mechanism comprises the rotatable driving clutch member 6 and the cooperating axially aligned rotatable upper and lower driven clutch members 7 and 8 respec-

tively for actuating the tub 2 and wringer 55 3. The driving clutch member 6 has the hub 9 and the rim 10 connected to the hub by the integral spokes 11. Upon the periphery of the rim is the worm gear 12, the teeth of which intermesh with the teeth of the worm 13 mounted upon the driving shaft 14 which is coupled to the drive shaft of the electric motor 4. The rim 10 also has in its sides the oppositely disposed annular V-shaped grooves 15 and 16 for engagement in 60 by the annular V-shaped flanges 17 and 18 respectively upon the driven clutch members 7 and 8 by means of which the driven clutch members are rotated from the driving clutch member.

The upper driven clutch member 7 has the annular cam groove 19 in its upper face which is eccentric to the axis of rotation of the driven clutch member. 20 is a segmental shoe slidably engaging in the groove and 75 provided with the transverse cylindrical recess 21. 22 is a pivoted tub actuating lever having the spherical head 23 at its free end fitting in the recess 21 of the shoe, there being sufficient clearance between this spherical 80 head and the base of the cylindrical recess to permit of the necessary longitudinal movement of the head in the recess while the lever is being laterally swung from one end of its travel to the other during the rotation of 85 the upper driven clutch member. This lever is non-rotatably secured to the pin 24 as by means of the key 25 and the pin is journalled in the side walls of the enlargement 26 upon the upper section of the housing 27. One 90 end of the pin extends outwardly beyond one of the side walls and is non-rotatably secured to the lever 28 as by means of the key 29, the free end of this lever being pivotally connected to the link 30, the opposite 95 end of the latter being pivotally connected to the reinforcement 31 at one end of the tub 2.

The lower driven clutch member 8 which is preferably connected to the annular V-shaped flange 18 by spokes, has the hub 32. The lower end of this hub has the diametrically opposite recesses 33 for engagement by a transverse pin 34 upon the vertical shaft 35. This shaft extends upwardly through the hub 9 of the driving clutch member 6 and also through the hub 36 of the upper driven clutch member 7, both of these hubs

being rotatable upon the shaft. This shaft is journaled at its lower end in the lower section of the housing 27 and near its upper end in the upper section of the housing 27 5 and has at its upper end the bifurcations 37 between which extends the tongue 38 of the wringer driving shaft 39 adapted to be operatively connected to the wringer rolls by the usual reverse gearing. To center the 10 lower end of the wringer driving shaft 39 and the upper end of the shaft 35, there is the axial pin 40 extending upwardly between the bifurcations 37 and engaging in the axial recess 41 in the lower end of the 15 shaft 39.

42 is a collar bearing upon the lower end of the lower section of the housing 37 and secured to the shaft 35 near its lower end by the transverse pin 43. 44 is a second 20 collar engageable with the lower end of the hub 9 of the driving clutch member 6 and secured to the shaft 35 by the transverse pin 44'. 45 is a third collar engageable with the upper end of the hub 9 of the driving 25 clutch member and secured to the shaft 35 by the transverse pin 45'. 46 is a fourth collar bearing against the upper end of the upper section of the housing 27 and secured to the shaft 35 by the transverse pin 47. These 30 four collars are alike with the exception that the upper or fourth collar 46 has the annular groove 48 in its lower face for engagement in by the balls 49 of an anti-friction bearing which also engage in an annular groove 50 35 in the upper face of the washer 51 surrounding the shaft 35. 52 is a thrust bearing surrounding the shaft 35 and engageable with the upper end of the hub 36 of the upper driven clutch member 7, and 53 is a coil 40 spring abutting the washer and the thrust bearing for yieldably forcing the upper driven clutch member 7 into driving engagement with the driving clutch member 6. 54 is a second coil spring surrounding the shaft 35 and abutting the driving clutch member 6 and the upper driven clutch member 7, this spring being of sufficient strength to raise the upper driven clutch member out of driving engagement with the driving clutch 45 member when the downward pressure of the coil spring 53 is relieved. 55 is a third coil spring abutting the collar 42 and the hub 32 of the lower driven clutch member 8 for yieldably forcing the lower driven clutch 50 member into driving engagement with the driving clutch member.

To relieve the upper driven clutch member 7 from the downward pressure exerted by the coil spring 53, there is the yoke 56 60 embracing the thrust bearing 52 and located below its outwardly extending annular flange 57 at its upper end. This yoke is rotatably secured to the vertically extending rod 58 which extends upwardly through the 65 upper section of the housing 27 parallel and

adjacent to the shaft 35 and has the cam member 59 secured thereto as by means of the transverse pin 60. This cam member has the depending V-shaped cam 61 engageable with the upper end of the boss 62 upon the upper part of the housing 27, the upper end of this boss being provided with the V-shaped groove 63 which is engageable by the cam 61 to permit of downward movement of the rod 58 and yoke 56 sufficiently to permit of the coil spring 53 exerting its downward pressure upon the thrust bearing 52 and upper driven clutch member 7. However, upon rotation of the rod 58, the cam 61 rides out of the groove 63 and upwardly upon the 70 end of the boss 62 thereby raising the rod and yoke as well as the thrust bearing, and consequently compressing the coil spring 53. As soon as this occurs, the coil spring 54 75 yieldably raises the upper driven clutch member out of driving engagement with the driving clutch member.

The housing 27 is located at one corner of the frame 1 of the washing machine and supports the vertical tubular leg 64 of the frame, the lower end of this leg engaging in the upper end of the upper section of the housing and being secured thereto by suitable means such as the set screw 65. This tubular leg 64 extends axially of the shaft 35 80 and preferably surrounds the upper end thereof. Also, the wringer driving shaft 39 extends upwardly through this tubular leg so that the latter in addition to forming a part of the frame of the washing machine, 85 houses part of the drive mechanism.

To rotate the rod 58 which controls the driving of the upper driven clutch member 7, there is the upper rod 66 extending substantially parallel and adjacent to the tubular leg 64 and having at its upper end the handle 67 adjacent to the bearing of the rod upon the frame. The lower end of this rod is non-rotatably secured to the rod 58, but permits of relative longitudinal movement 90 thereof which is accomplished by securing the nut 68 to the lower end of the upper rod and providing this nut with the longitudinally extending slots 69 which are slidably engaged in by the pins 70 extending transversely from the rod 58.

The electric switch 71 for controlling the motor is also located at the same corner of the washing machine and adjacent to the handle 67. The wiring 71' running from this switch to the electric motor passes through the upper horizontal tubular member 72 at one side of the frame and through the vertical tubular leg 73 forming part of the frame 1 and out through an opening near the lower end of this tubular leg. This tubular leg is at the corner of the frame near which the electric motor is mounted.

To retain the segmental shoe 20 within the cam groove 19 so that it cannot move vertically 130

5 cally relative to the upper driven clutch member 7, I have provided the plate 74 secured to the upper face of the upper driven clutch member and extending slightly over the cam groove to engage the upper edge of the shoe, this plate, however, not interfering with the movement of the spherical head 23 upon the tub actuating lever.

10 To lubricate the friction surfaces of the different members within the housing 27, the plate 74 is provided with the apertures 75 and the annular flange 17 upon the upper driven clutch member 7 has the vertically extending passageways 76 therethrough.

15 Also, the rim 10 of the driving clutch member 6 has the vertical passageways 77 extending therethrough between the annular V-shaped grooves 15 and 16 therein. Furthermore, the base of the shoe 20 and that

20 portion of the upper driven clutch member forming the base of the cam groove 19 are apertured at 78 and 79 respectively for the passage of the lubricant. The upper section of the housing 27 has the threaded

25 opening 80 for permitting of the insertion of the lubricant into the housing, this opening being normally closed by the plug 81. To permit of draining the lubricant out of the housing, I have provided the lubricant

30 passageways 82 in the lower end of the lower section of the housing and opening into the housing beyond the lower collar 42 and into the bore 83 below the lower end of the shaft 35. This bore is normally closed by the plug 84.

What I claim as my invention is:

1. In a drive mechanism for washing machines, the combination with a rotatable driving clutch member, of a cooperating rotatable driven clutch member, a pivoted lever having a cam engagement with said driven clutch member, a second rotatable driven clutch member cooperating with said driving clutch member, and a shaft extending through said first-mentioned driven clutch member and said driving clutch member and secured to said second mentioned driven clutch member.

2. In a drive mechanism for washing machines, the combination with a frame for a washing machine including a vertically extending leg, of a rotatable driving clutch

member, a cooperating rotatable driven clutch member, and a shaft connected to said driven clutch member and extending upwardly within said vertically extending leg.

3. In a drive mechanism for washing machines, the combination with the frame for a washing machine including a vertically extending tubular member, of a rotatable driving clutch member, a cooperating rotatable driven clutch member, a member actuated from said driven clutch member, and a housing for inclosing said clutch members, carrying said vertically extending tubular member.

4. In a drive mechanism for washing machines, the combination with a rotatable driving clutch member, of a cooperating rotatable driven clutch member having an eccentric groove, a segmental shoe slidably engaging in said groove and provided with a transverse recess, and a pivoted lever having a spherical head at one end thereof engaging in said recess.

5. In a drive mechanism for washing machines, the combination with a rotatable driving clutch member, of a cooperating rotatable driven clutch member having a cam groove, a shoe slidably engaging in said groove, a lever connected to said shoe, and means for retaining said shoe in said groove.

6. In a drive mechanism for washing machines, the combination with a rotatable driving clutch member, of a cooperating rotatable driven clutch member having an eccentric groove, a segmental shoe slidably engaging in said groove and provided with a transverse recess, a pivoted lever having a spherical head at one end thereof engaging in said recess, and means upon said driven clutch member for maintaining said shoe in engagement with said groove.

7. In a drive mechanism, the combination with a rotatable driving clutch member, of a cooperating rotatable driven clutch member having a cam groove, a shoe slidably engaging said groove, a lever connected to said shoe, and a member secured to the driven clutch member for retaining said shoe in said groove.

In testimony whereof I affix my signature.
EDGAR D. MISNER.
